UNITED STATES PATENT OFFICE

THOMAS J. FLANAGAN, OF NEW HAVEN, CONNECTICUT

AMBULANCE COT

Application filed April 26, 1928. Serial No. 273,042.

My invention relates to ambulance cots, and more particularly to cots or stretchers for ambulances in which means are provided for supporting the cots or stretchers in an elevated horizontal position when carried therein.

Generally speaking, the invention relates to that form of a cot or stretcher for ambulances in which legs or other means are provided for supporting the cot, the legs at one end, preferably the head of the cot, being relatively short in order that the cot may not have to be raised much above the floor of the ambulance in placing it in the ambulance, the latter being provided with an inclined track on which the legs may rest, the track being inclined upwardly towards the front of the ambulance, so that as the cot or stretcher is inserted into the ambulance, the same becomes elevated above the floor. The foot of the cot is provided with relatively long legs, so that when the cot is fully inserted into the ambulance it rests in the substantially horizontal position with the patient at a substantial distance above the floor. While cots of this type are of great convenience in placing patients in an ambulance, they present the difficulty that the legs at one end are shorter than those at the other, requiring that the head of the cot be supported by an attendant when out of the ambulance in order that the body of the patient may be kept horizontal.

It is an object of the present invention to provide a cot or stretcher which, while presenting the ease of the usual cot in being placed in an ambulance, is provided with a supporting means by which the cot may be supported in a substantially horizontal position when withdrawn from the ambulance.

A further object of the invention is to provide a cot having the above characteristics in which the cot may be supported in a substantially horizontal position, either on an inclined way or on a horizontal support.

A still further object of the invention is to provide a plurality of supporting means on a cot which may be used at will and which do not interfere with one another.

In a more specific aspect, the invention con-

templates a cot having a foldable supporting element which may be readily brought into use when occasion demands.

To these and other ends, the invention consists in the novel features and combination of parts to be hereinafter described and claimed.

In the drawings,

Fig. 1 shows a cot according to my invention supported in an ambulance body, the latter being shown in a diagrammatic manner;

Fig. 2 is an end view of the same;

Fig. 3 is a sectional view along line 3—3 of Fig. 2, but partly broken away;

Fig. 4 is a sectional view of the head of the cot, the remaining parts being broken away;

Fig. 5 is a view of the cot withdrawn from the ambulance and resting on a horizontal support; and

Fig. 6 is a sectional view along line 6—6 of Fig. 5.

Referring now to the drawings in which I have illustrated my invention by showing a preferred embodiment thereof, the reference numeral 7 indicates in general the body of an ambulance or the like, the ambulance being shown in a somewhat diagrammatic manner in the drawings, and including a floor 8, inclined guideways 9 which rest on and are attached to the floor 8 at the rear 10 of the ambulance and are provided with upwardly inclined forward ends 11 which are supported from floor 8 in any suitable manner, as, for example, by means of straps 12 and 13.

The reference numeral 14 indicates in general my improved cot which comprises a body 15 which is provided with a hinged head-rest 16 which may be elevated to a plurality of positions by means of pawls, one pawl only being shown, it being readily understood that there are two of these pawls, one at either side of the head-rest, pawls 17 engaging a rod 18 which extends transversely of the cot body 15 and is supported in oppositely disposed short legs 19, which are braced by means of straps 20 and are provided with rollers 21 mounted on rod 22 extending transversely of the cot and supported in legs 19. At the opposite end of cot body 15 are a pair

of relatively long legs 23 braced by means of straps 24 and supported on rollers 25 mounted on transversely extending rod 26. As is usual, a pad 27 is supported on an upper part of the cot body 15.

The manner of use of the cot and ambulance described above will be readily understood and may be briefly described as follows: When it is desired to insert the cot 10 into the ambulance, the cot is elevated in a horizontal position until the short legs may be placed on the guideways at the rear end of the vehicle, whereupon the cot may be pushed into the ambulance body, the attendant supporting the outer end of the cot raising that end as the front end of the cot mounts the inclined way, so that when the cot is 15 fully inserted into the ambulance body, the long legs may rest on the rear end of the guideway with the cot in a substantially horizontal position.

When a cot of this type is not carried on the guideways of the ambulance, it is necessary for an attendant to support the end 20 having the short legs, since otherwise this end of the cot would be so low as not only to place the patient in an uncomfortable but often in a dangerous position. To the end that the cot may be supported outside the 25 ambulance in a horizontal position, the improved cot of the present invention is provided with means for supporting the head of the cot at the same distance from the floor, or other horizontal support, as the foot of 30 the cot. As a suitable and preferred means for this purpose, legs 28 and 29 are provided and pivotally supported on opposite sides of cot body 15 near the head of the cot, legs 28 and 29 being interbraced by means of 35 straps 30 and 31 and provided with castors 32 and 33, respectively. Pivotally supported on legs 28 and 29, near the lower ends thereof, are links 34 and 35, the opposite ends of links 34 and 35 being supported from holes 36 40 and 37 in the cot body 15 by means of jointed pins 38 and 39, one part of each pin being secured in its respective link and the hinged ends 41 and 40 thereof being adapted to prevent accidental dislodgment of the pins from 45 the holes in which they may be placed. As shown in the drawings, the hinged ends 40 and 41 normally hang downwardly and in this position form T-heads for the pins. At 50 the rear end of the ambulance body an L-shaped plate 42 is secured to the floor 8 by suitable means, as, for example, bolts 43, plate 42 having an arm 44 which engages either of rods 22 and 26 to hold the cot against movement outwardly of the ambulance body. 55 When my improved cot is carried in the ambulance body the auxiliary supporting means or legs 28 and 29 are folded up underneath the cot body, as shown in Fig. 1 of the drawings, the pins 38 and 39 being carried 60 in the holes 37. When the cot is withdrawn

from the ambulance body, the pins 38 and 39 may be withdrawn from holes 37 and inserted into holes 36 in which position legs 28 and 29 will be substantially vertical, as shown in Fig. 5 of the drawings, and the cot may be supported in a horizontal position on a floor or the like. When it is desired to insert the cot into the ambulance again, it is only necessary to withdraw the pins from holes 36 and insert them into holes 37 whereupon the auxiliary supporting means is folded up out of the way and the cot may be inserted into the ambulance without interference by this auxiliary supporting means. If desired, the long legs and the auxiliary supporting means or legs may be of such a length that the bottom of the short legs is at the same height as the floor of the ambulance body, whereupon it is simply necessary to roll the cot over to the ambulance body and raise it sufficiently to clear the arm on L-shaped plate 42, whereupon the auxiliary supporting means or legs 28 and 29 may be folded up under the cot body, and the cot inserted into the ambulance. 70 75 80 85

From the above description of the nature of my invention and its mode of operation, it will be readily understood that I have provided an ambulance cot or the like, on which a patient may be moved about and placed in an ambulance more readily and with less danger than is the case with the usual form of cots. 90 95

While I have shown a preferred embodiment of my invention, it is to be understood that the same is not to be limited to all the details shown but is capable of modification and variation within the spirit of the invention and the scope of the appended claims. 100

What I claim is:

1. In a cot or the like, a cot body, a pair of relatively long legs at one end of the body, a pair of relatively short legs at the other end of the body and a pair of legs at an intermediate point in the cot body, said last named legs being of substantially the same length 105 110 115 as the long legs.

2. A cot for an ambulance provided with an inclined guideway on which the cot may be supported, said cot being provided with means for supporting the cot body in a substantially horizontal position on the guideway, and means for supporting the cot body in a horizontal position on a horizontal support, said means comprising a plurality of legs for said cot, certain of said legs being of equal length and the remaining legs being relatively shorter, the legs of equal length being disposed on the cot body at one end thereof, and at an intermediate point and the short legs being at the other end of the cot. 120 125

In witness whereof, I have hereunto set my hand this 18th day of April, 1928.

THOMAS J. FLANAGAN.
